OSCAR LINDER, OF CHICAGO, ILLINOIS, ASSIGNOR TO WESTERN ELECTRIC COMPANY,
INCORPORATED, OF NEW YORK, N. Y., A CORPORATION OF NEW YORK.

PROCESS OF AND APPARATUS FOR ELECTROLYSIS.

1,371,698.

Specification of Letters Patent. Patented Mar. 15, 1921.

Application filed January 11, 1918. Serial No. 211,382.

To all whom it may concern:

Be it known that I, OSCAR LINDER, a citizen of the Republic of Switzerland, residing at Chicago, in the county of Cook and State 5 of Illinois, United States of America, have invented certain new and useful Improvements in Processes of and Apparatus for Electrolysis, of which the following is a full, clear, concise, and exact description.

10 This invention relates to an improved process of and apparatus for electrolysis, and more particularly to an improved process of and apparatus for completely eliminating salts and other ionized chemicals from 15 their aqueous solutions by means of electrolysis.

Electrolysis of aqueous solutions is commonly carried on in practice for three main purposes. Its first and principal use is for 20 the purpose of precipitating metals on the cathode, as, for example, in electro-plating and electrolytic refining of metals. A second use is for the purpose of obtaining certain chemicals, mostly elements, from their 25 compounds by electrolysis, as for example, in the manufacture of chlorin, hydrogen, oxygen, etc. A third application, though of less importance, is the use of electrolysis in quantitative chemical analysis.

30 It is well known in the art that electrolytic deposition, while frequently efficient in electrolyzing solutions containing ionized chemicals at a fairly high concentration, becomes less so with decreasing concentration 35 for two principal reasons: first, because the ohmic resistance increases, and second, because secondary reactions are apt to develop which lower the efficiency of the process; for example, a common complaint is that the 40 electrolyte turns acid.

In all practical applications of electrolysis for the above enumerated purposes, it is comparatively simple to avoid such complications, since there is a possibility of keeping 45 the electrolyte always well saturated with salts, so that the efficiency of the process remains high and the ohmic resistance of the electrolyte low. In electro-plating and electrolytic refining of metals this is generally accomplished automatically, because an 50 equal or nearly equal amount of metal is dissolved from the anode as is precipitated at the cathode. Any deficiency is made up by adding to the electrolyte a sufficient quantity

of a salt of the same or similar composition 55 as the one contained therein. In the quantitative analysis, where all of a certain metal in solution is to be precipitated, it is customary to add to the electrolyte salts commonly known as conducting salts. These salts aid 60 in the action of the electrolysis by conducting the current, but do not actually separate out at the electrodes.

There are other uses for electrolysis besides the ones above cited, as for example, 65 where the salts are to be completely eliminated from waste liquors, or from wash waters, or from solutions which cannot be contaminated with conducting salts. In these cases the difficulties above explained, 70 due to decreasing concentration of the electrolyte, cannot be readily overcome, for economic reasons, in the manner described, and it has, therefore, been impractical in the past to employ electrolysis in many such 75 cases. There are many instances where electrolysis might be applied for such purposes, but it has been found that its use is impractical, mainly on account of the secondary reactions which take place prominently 80 when certain dilutions are reached which render complete removal of all constituents practically impossible. Thus for example, the electrolyte may turn acid and the current will then preferably liberate hydrogen and 85 oxygen at the electrodes in place of a metal and an acid radical, the removal of which is desired.

It is the object of this invention to overcome the above described difficulties, and 90 this has been accomplished by placing the anode in an electrolyte which is contained within a porous container, and placing the porous container in the electrolyte into which the cathode is immersed. This constitutes an arrangement similar to the one used in the Leclanché primary battery in 95 which a porous cup serves the same purpose, namely that of separating mechanically but not electrically the electrolyte surrounding 100 and the products of the electrolytic action formed at the anode, from the electrolyte surrounding and the products of the electrolytic action formed at the cathode. In place of a porous container any equivalent 105 expedient, such as a porous diaphragm, may be used.

By using such an arrangement it is not

only possible to completely separate the product separated out at the cathode from that separated out at the anode, even if one or both products are soluble in the electrolyte, but it is also possible, by the use of two or more anodes to regulate the reaction—that is, the acidity or alkalinity, of the electrolyte surrounding the cathode. Another advantage of such an arrangement lies in 10 the fact that the ohmic resistance of the whole cell can be kept comparatively low, because the anode can be immersed in an electrolyte of high conduction. By proper design and construction of the cell, conditions can be obtained wherein substantially 15 all parts of a salt can be quantitatively removed from a solution and at a comparatively high efficiency.

The essential conditions for an economical 20 elimination of ionized chemicals from aqueous solutions consist: first, in keeping the products which are liberated at the electrodes separated; second, in preventing disturbing secondary chemical reactions; and 25 third, in keeping the ohmic resistance of the cell reasonably low. By means of this invention the first condition is met by the use of a porous cup or diaphragm, which separates mechanically but not electrically the 30 electrolyte surrounding the anode from that surrounding the cathode. The second condition is met by using two or more anodes, each one surrounded by its own electrolyte and separated from the electrolyte surrounding 35 the others and from that surrounding the cathode by porous diaphragms, or by immersing all anodes in one electrolyte which is separated from the electrolyte surrounding the cathode by a porous diaphragm; 40 also by using anodes of different materials, for example a soluble and an insoluble anode, and by proper regulation of the current flow through each anode whereby conditions can be obtained at will which will 45 tend to render the electrolyte surrounding the cathode neutral, acid or alkaline. The third condition can be met by surrounding the anode or anodes with an electrolyte of 50 low ohmic resistance and by proper proportioning of the cell.

The improved process of this invention may be best explained by referring to the accompanying diagrammatic drawings, in which:

55 Figure 1 is a sectional front elevation of an electrolytic cell in its simplest form, equipped with a porous cup;

Fig. 2 is an electrolytic cell provided with two porous cups;

60 Fig. 3 illustrates a sectional elevation of an electrolytic cell equipped with a porous partition for separating the electrolytes;

Fig. 4 is a plan view thereof;

Fig. 5 illustrates a sectional elevation of 65 an electrolytic cell equipped with two po-

rous partitions for separating two anodes and their associated electrolytes from the cathode and its electrolyte;

Fig. 6 is a plan view thereof;

Fig. 7 is a sectional elevation in diagrammatic form of the cell illustrated in Fig. 1 together with the required electrolyte circulating apparatus;

Fig. 8 is a similar view of the cell illustrated in Fig. 3, together with its electrolyte circulating apparatus;

Figs. 9, 11, 12, and 13 are sectional elevations of electrolytic cells equipped each with a porous partition for separating the anodes and their associated electrolytes from the cathodes and their electrolytes, embodying different constructions of the electrodes;

Fig. 10 is a plan view of the cell illustrated in Fig. 9, and

Fig. 14 is a sectional elevation of a cell 85 equipped with a porous cup, showing the use of a metal lining of the receptacle as a cathode.

Fig. 1 of the above illustrations shows an electrolytic cell 10 in which is contained the 90 electrolyte 11 which is to be subjected to electrolysis. Suspended in any suitable manner in this electrolyte is the cathode 12. A porous cup 13 containing the anode 14 and its electrolyte 15 is positioned in the cell 95 10. The cathode 12 and anode 14 are connected to any suitable source of electrical energy, as indicated in this figure.

Fig. 2 shows a similar electrolytic cell 16 containing an electrolyte 17 in which is suspended the cathode 18. This cell carries the two porous cups 21 and 22, in each of which is positioned anodes 23 and 24 respectively in the desired electrolyte. The anode and cathode are connected to some 105 suitable source of electrical energy and preferably but not necessarily through a rheostat such as 25.

The porous cups 13, 21, and 22 indicated in these two figures are preferably cylindrical in form and are surrounded by the electrolyte contained in the cells 10 and 16.

Figs. 3 and 4 show an electrolytic cell 28 fitted with a porous partition or diaphragm 29. This partition separates this cell into 115 the two chambers 30 and 31. The anode 32 is placed in the chamber 31, and the cathode 33 in the chamber 30.

Figs. 5 and 6 illustrate an electrolytic cell similar to that shown in Figs. 3 and 4, the 120 cell 35 in this case being fitted with two partitions 36 and 37, dividing it into the chambers 38, 39, and 40, two anodes 41 and 42 being positioned in the chambers 38 and 40 and a cathode 43 in the chamber 39. Obviously a cell such as 35 could readily be constructed with any desired number of partitions, thereby providing chambers separated from each other by a porous diaphragm, and thereby providing a cell in 130

which any desired number of different kinds of electrolyte may be utilized and in which these electrolytes will be maintained separated from one another. The anodes and cathode of this cell are likewise connected to any suitable source of electrical energy, if desired through an electrical rheostat such as 44.

Fig. 7 indicates an electrolytic cell which is similar in construction to that illustrated in Fig. 1 connected to the desired electrolyte circulating system. Thus the cell 50 there shown is fitted with a porous cup 51 containing the anode 52 and its associated electrolyte. The electrolyte 53 which is to be subjected to electrolysis contained in the cell 50 has suspended therein the cathode 54. The anode 52 and cathode 54 are connected to any suitable source of electrical energy. The electrolyte 53 is fed from the cell 50 by means of any suitable liquid conveying means such as an overflow 55 into a settling tank 56. From the settling tank the electrolyte is discharged through the liquid conveying means 57 to a storage or wash tank 58. The flow of the liquid 53 from the cell 50 to the settling tank 56 and from said tank to the storage tank 58 is gravitationally produced. Connected to the storage tank 58 is the pipe 59 which is connected to any suitable pump 60 diagrammatically indicated in the figure, the other side of the pump being connected with the pipe 61 which feeds the electrolyte into the cell 50. It will be evident, therefore, that with an apparatus such as shown in Fig. 7 the electrolyte 53 will be continually circulated, due to gravity and the action of the pump 60, from the cell 50 through the settling tank 56 and the storage or wash tank 58. In this circulation the electrolyte is subjected to the electrolytic action of electrolysis through the cell 50, from which action it is absolutely independent in the settling tank 56 or the storage or wash tank 58. The settling tank 56 is not always necessary, but if required will act to clarify the solution from any sediment or impurities collected therein during the process of the complete operation. The tank 58 likewise is not always required and serves as a means for storing the electrolyte, or as an actual wash tank in which the electrolyte 53 may be utilized to perform any washing or other operations desired.

Fig. 8 illustrates a cell of the type shown in Fig. 2, together with an electrolyte circulating system. In this figure the electrolytic cell 64 is fitted with a partition 65 which divides this cell into the compartments 66 and 67. The compartment 66 contains the anode 68 and its associated electrolyte, and the compartment 67 the cathode 69 and the electrolyte 70 which is to be subjected to the action of electrolysis. The

electrolyte 70 is circulated from the cell 64 by means of the pipe 71 to the filter press 72, and from there by means of the pipe 73 to the storage or wash tank 74. Obviously any type of filter press or settling means may be utilized for the press 72 and the tank 74 illustrated in Figs. 8 and 7 respectively. The electrolyte 70 is circulated from the wash tank 74 by means of the pump 75 through the pipe connection 76 which interconnects the pump 75 with the tank 74, and the pipe connection 77 which interconnects the pump with the cell 64. In addition to circulating the electrolyte 70 it may also be found convenient and useful to circulate the electrolyte in which the anode 68 is suspended. When this is desired a storage tank such as 80 containing this electrolyte 81 is connected by means of the piping 82 and the interposed pump 83 with the compartment 66 of the cell 64. The compartment 66 is also directly connected by means of the pipe 84 with the storage tank 80.

In a system such as shown in Fig. 8, therefore, the electrolyte 70 which is to be subjected to electrolysis will be circulated from the cell 64 through the filter press 72 and the wash or storage tank 74 by gravity and will be pumped from the wash tank by means of the pump 75 back to the cell 64. Likewise the electrolyte 81 will be gravitationally fed from the compartment 66 of the cell 64 to the storage tank 80 and from said tank will be pumped back to said compartment by means of the pump 83. It will be evident, therefore, that in a system of the type illustrated in Fig. 8, the electrolyte 70 associated with the cathode as well as the electrolyte 81 associated with the anode will be continuously circulated.

Figs. 9 and 10 illustrate an electrolytic cell similar to the one shown in Figs. 5 and 6, with the exception that the two anodes 90 and 91, made of dissimilar materials, are placed in one anode compartment 92. The cathode compartment 93 of the cell contains the cathode 94. The two anodes 90 and 91 are either in direct connection with an external source of electrical energy, as indicated in Fig. 9, or, as shown in Fig. 10, they may be connected through a rheostat such as 95. In the first instance, the amount of current flowing through the anodes is preferably controlled by the shape, dimensions, and depth of immersion of both anodes. In the other case, current regulation may be controlled partly in this manner, partly by means of the rheostat, or entirely by the rheostat.

Fig. 11 illustrates an electrolytic cell similar to that shown in Fig. 3, but shows the anode 96 and the cathode 97 in a horizontal position instead of a vertical position, the anode 96 being placed on the bottom of the anode compartment 98 and the cathode 130

on the bottom of the cathode compartment 99.

Fig. 12 shows another modification and illustrates a cell equipped with a horizontal anode 100 which is covered with a loose metal 101 in powder, sponge, or granular form. The cathode 102 in this instance comprises the lining of the container 103. The container is divided into the anode compartment 104 and the cathode compartment 105 by the porous partition 106. In this construction of an electrolytic cell the loose metal placed on the anode may be the same or of a different character than that from which the anode itself is made. When the anode itself and the loose metal are composed of the same material the loose metal will go into solution in the electrolyte in the anode compartment 104, and thereby reduce or prevent the deterioration or dissolution of the solid anode, and will therefore serve the purpose of utilizing an anode composed of a loose material in powder, sponge, moss, or granular form instead of a solid material. When the loose metal and anode itself are composed of different materials the arrangement would be the equivalent of two solid anodes of dissimilar materials.

Fig. 13 indicates a modification of the electrolytic cell shown in Fig. 12, in that a solid anode material 110 is placed on a horizontal anode 111, the two being placed at the bottom on an anode compartment 112 separated from the cathode compartment 113 by a porous partition 114.

Fig. 14 illustrates another modification of an electrolytic cell in which the container 115 is fitted with a metallic lining 116 which serves as the cathode of the cell. Immersed in the cathode electrolyte 117 is a porous cup 118 which carries the anode 119 and the anode electrolyte 120.

Obviously any desired combination may be made of the cells illustrated in Figs. 1 to 6 and 9 to 14 inclusive or the various elements of the circulating systems illustrated in Figs. 7 and 8 inclusive. Thus a cell having any desired number of electrolytic compartments may be used, and the electrolyte in any one or all of said compartments may be circulated, said circulating system including any of the well known types of apparatuses used for the purpose of fluid filtration, clarification, etc., and also containing any suitable or desired type of fluid storing means and any convenient circulating means. Also the electrodes may be of any desired construction and may be placed in any desired position in the cell.

In the preferred application of this invention the solution to be electrolyzed is generally passed through a settling tank, as illustrated in Fig. 7, in which any sediment is allowed to settle out or through a filter, diagrammatically illustrated in Fig. 8, in which

such sediment is filtered out. These operations are desirable in cases where the metallic deposit at the cathode is in very spongy form, in which condition it does not adhere well to the cathode and consequently is partly carried along by the circulating electrolyte, and in cases where partial precipitation of the salts in the electrolyte in basic form takes place.

In most instances of the practical application of this invention there is an accumulation of some of the products of the electrolysis in the porous cup or compartment surrounding the anode. If this accumulation becomes excessive there is likely to be considerable diffusion of these products into the cathode compartment, and in order to avoid this, the electrolyte such as 81 surrounding the anode 68, illustrated in Fig. 8, should be circulated either intermittently or continuously, depending upon the action desired, by some means, preferably by the pump 83, such as illustrated in Fig. 8. Instead of actually circulating the electrolyte 81 it is in some cases preferred to keep it at a uniform concentration by continuously or intermittently feeding in a small amount of water by any ordinary means, and allowing the electrolyte to overflow through the pipe 84 into the storage tank 80. The electrolyte 81 is generally of value since part of the original cathode electrolyte and the anode material may be recovered from it.

The invention herein described permits of so many variations and is applicable to so many conditions that it is not feasible to point out all the applications of the invention herein. The invention is obviously not limited to the examples and to the conditions cited, but can be employed in all cases where complete or substantially complete removal of salts or chemicals is desired from aqueous solutions, as set forth in the appended claims. These solutions may contain one or more salts and in many cases separation of these salts can be effected by the utilization of this invention.

As a specific example of the application of the process, reference will be made to the operation of freeing the wash water used in washing vulcanized fiber from zinc chlorid. If electrolysis is attempted without the arrangement hereinbefore described, hydrogen and zinc will be deposited at the cathode and chlorin and oxygen at the anode and the electrolyte will become strongly acid, so that it works at a very low efficiency and complete removal of the zinc chlorid becomes impractical. In this case, it is preferable to subject the wash water to electrolysis, using a zinc cathode and a zinc anode, the latter to be surrounded by a zinc chlorid solution inclosed in a porous cup or separated from the cathode electrolyte by a porous diaphragm, as hereinbefore described. With

this arrangement the zinc is precipitated at the cathode and the chlorin liberated at the anode in substantially equivalent proportions and almost quantitatively. Under such conditions the liberation of oxygen at the anode and hydrogen at the cathode is prevented, even at the lowest concentrations, and the electrolyte is prevented from becoming acid and becomes, on the contrary, 10 alkaline. If a carbon anode is used in place of the zinc anode there will be some liberation of chlorin and oxygen at the anode and some formation of hydrochloric acid in the electrolyte surrounding the cathode. By 15 using both a zinc and carbon anode, either in the same electrolyte or each in a separate porous cup or partition, as illustrated in Figs. 2 and 5, conditions will obtain whereby the electrolyte surrounding the cathode 20 may be maintained acid, alkaline, or neutral, at will. This will be evident from the fact that the portion of the current which flows from the carbon anode to the zinc cathode has a tendency to form hydrochloric acid in 25 the electrolyte surrounding the cathode, and that portion which flows from the zinc anode to the zinc cathode has a tendency to render it somewhat alkaline, and therefore the current flow in these circuits may be regulated by a rheostatic control or by the size 30 of the electrodes or the depth of their immersion, so that these two actions will either neutralize one another and thus keep the solution neutral, or whereby either one action 35 or the other will predominate and make the solution either acid or alkaline.

In some cases partial elimination of the ingredients in the solution by precipitation is preferable and may be accomplished by so 40 choosing conditions as to cause the electrolyte surrounding the cathode to become alkaline. For example, in the hereinbefore referred to process of removing zinc chlorid 45 from the wash water in the manufacture of hard fiber this is easily accomplished by employing a zinc anode immersed in a solution of zinc chlorid, which is separated from the solution to be electrolyzed by a porous diaphragm. In this case the reaction 50 is so controlled that part of the zinc in the solution is precipitated out as zinc hydroxid, which is allowed to settle out in a settling tank, such as illustrated in Fig. 7, or filtered out in a filter press such as illustrated in 55 Fig. 8.

For the purpose of separating the electrolytes, any kind of cup, diaphragm, or partition made of any desired material may be utilized. Thus, a mineral diaphragm 60 such as clay or unglazed porcelain, an animal diaphragm such as skin, leather, hardened gelatin, coagulated albumin, or pig's bladder; or vegetable diaphragms such as fiber, parchmentized paper, viscose, etc.

65 The cathode may be of any desired metal,

or of carbon or graphite and in any desired shape.

Instead of using two anodes immersed in the same compartment, it is possible to use a single anode, allow it to become partly 70 or wholly coated or covered with another metal or surround it with another metal in loose form, and thus have the same effect as having two separate anodes in the same electrolyte. Obviously, in this manner the flow 75 of electric current may be regulated to a certain degree by covering the one anode material more or less with the other anode material. In this manner a certain amount of regulation of the flow of current through 80 each part of the anode is also possible.

Where two or more anodes are employed and each one is immersed in a separate electrolyte, separated from the others by a porous diaphragm, these anodes may be either 85 of the same or of different materials. The use of two or more anodes of the same material is sometimes preferred, and variations are introduced into the electrolysis by choosing the proper electrolyte, current and current density for each anode. 90

The choice of the electrolyte in which the anode or anodes are immersed must be determined for each separate case. As a general rule, a salt will be chosen which is 95 identical to that which is to be removed from the solution into which the cathode is immersed. This is not, however, necessary and a great many variations may be introduced by choosing electrolytes of different 100 compositions and concentrations.

Obviously the invention is not limited to the preferred embodiment thereof herein shown, other forms and applications thereof being contemplated, as set forth in the following claims. 105

What is claimed is:

1. The method of eliminating a salt or other ionized chemical from its aqueous solution, which consists in electrolyzing the 110 solution between a cathode and a plurality of anodes of dissimilar materials, each anode being immersed in its own electrolyte each of said electrolytes being separated from each other and from said solution by a 115 porous diaphragm.

2. The method of eliminating a salt or other ionized chemical from its aqueous solution, which consists in electrolyzing the solution between a cathode and a plurality 120 of anodes of dissimilar materials, all anodes being immersed in an electrolyte which is separated from said solution by a porous diaphragm.

3. The method of regulating and controlling the reaction of a solution containing ionized chemicals, which consists in subjecting the solution to electrolysis between a cathode and a plurality of anodes of dissimilar materials, each one of said anodes 125 130

being immersed in an electrolyte which differs from said solution in composition or concentration, and in separating said electrolytes from each other and from said solution by porous diaphragms.

4. The method of regulating and controlling the reaction of a solution containing ionized chemicals, which consists in subjecting the solution to electrolysis between a 10 cathode and a plurality of anodes, said anodes of dissimilar materials being immersed in an electrolyte which is separated from said solution by a porous diaphragm.

5. The method of separating a water soluble salt or other ionized chemical from other salts or chemicals by subjecting an aqueous solution of the mixture of these chemicals to the action of electrolysis between a cathode and a plurality of anodes of dissimilar 20 materials, the anodes being immersed in an electrolyte which is separated from said solution by a porous diaphragm.

6. An electrolytic apparatus for the removal or deposition of salts or their equivalents from their aqueous solutions, comprising in combination, a cathode, a solution from which the salts are to be removed in which said cathode is immersed, a plurality of anodes of dissimilar materials, an electrolyte for each of said anodes, and porous diaphragms separating said electrolytes from each other and from said solution.

7. An electrolytic apparatus for the removal or deposition of salts or their equivalents from their aqueous solutions, comprising

ing in combination, a cathode, a solution from which the salts are to be removed in which said cathode is immersed, a plurality of anodes of dissimilar materials, a common electrolyte for said anodes, and a porous 40 diaphragm separating said electrolyte from said solution.

8. An electrolytic apparatus for the removal or deposition of salts or their equivalents from their aqueous solutions, comprising in combination, an electrolytic cell, a plurality of anodes of dissimilar materials, a cathode, a solution from which the salts are to be removed in which said cathode is immersed, an electrolyte for each of said 50 anodes, and means for separating said electrolytes from each other and from said solution whereby diffusion between said electrolytes and said solution is prevented.

9. An electrolytic apparatus for the removal or deposition of salts or their equivalents from their aqueous solutions, comprising in combination, an electrolytic cell, a cathode, a solution from which the salts are to be removed in which said cathode is immersed, a plurality of anodes of dissimilar 60 materials, an electrolyte for each anode in which said anodes are immersed, and porous diaphragms whereby said electrolytes are separated from each other and from said 65 solution.

In witness whereof, I hereunto subscribe my name this 28th day of December, A. D. 1917.

OSCAR LINDER.
